TURBINE BLADING

Robert C. Allén, Wauwatosa, and James Wilson,
West Allis, Wis., assignor to Allis-Chalmers
Manufacturing Company, Milwaukee, Wis., a
corporation of Delaware

Application May 8, 1939, Serial No. 272,414

12 Claims. (Cl. 253—77)

This invention relates to turbine blading and more particularly to the manner of assembling and mounting impulse blading in high pressure and high temperature superimposed or topping turbine units.

The design of efficient impulse blading for elastic fluid turbines which are operated by high temperature and high pressure driving fluids and which operate at high relative speeds necessitates the use of blades of relatively great width which present spaced concave convex passage defining surfaces disposed in nested or in partially nested relationship. The driving fluid is applied intermittently by means of circumferentially spaced nozzles or groups of nozzles and the driving fluid subjects the blades to forces that may amount to many hundreds of pounds per blade. Consequently, when blades of great relative width are employed under conditions of high rotative speed and high temperature and pressure, the use of circumferential retaining grooves becomes impractical because of the great axial width of the retaining rims at the sides of the grooves and also because of the great difficulty of providing a suitable closing or locking device for holding the last blade in place.

The usual practice is to enlarge the circumferential retaining groove at one or more points to permit the insertion and removal of the blades and the last blade or blades to be inserted are secured in position by means of suitable wedging and locking members. Enlarging the circumferential retaining groove materially weakens the rim portions of the groove in the region of the enlargement and the high bending moments set up by the intermittent application of the driving fluid renders the obtainment of a stable structure highly impractical. In fact, there is no known manner of inserting and securing the last blade in a circumferential blade retaining groove which is practical and which will permit the use of highly efficient passages under conditions of maximum capacity and maximum temperature.

It is therefore an object of this invention to provide a novel blade assembly wherein each blade of a circumferential blade row in which the spaced concave convex passage defining surfaces on adjacent blades are disposed in nested or in partially nested relationship, is secured to the turbine spindle in exactly the same manner.

Another object of this invention is to provide a novel blade assembly wherein the blades co-acting to form a circumferential blade row, in which the spaced concave convex passage defining surfaces on adjacent blades are disposed in nested or in partially nested relationship, are mounted in a circumferential row of spaced axially extending grooves.

Still another object of this invention is to pro-

vide a novel blade retaining grooving arrangement for turbine spindles.

A further object of this invention is to provide a novel method of inserting blades in a turbine spindle to form a circumferential blade row in which the spaced concave convex passage defining surfaces on adjacent blades are disposed in nested or in partially nested relationship.

The invention accordingly consists of the method of blade insertion and of features of construction, combinations of elements, and arrangement of parts as more fully pointed out in the appended claims and in the detailed description in which:

15 Fig. 1 is a partial sectional view of the turbine embodying the invention;

Fig. 2 is a sectional view of a portion of the turbine spindle taken on line II—II of Fig. 1;

20 Fig. 3 is a view taken on line III—III of Fig. 1 with a portion of the shrouding broken away to show the cross-sectional configuration of the blades and fluid passages;

25 Fig. 4 is a bottom plan view of the blades for a circumferential blade row disposed in cooperative relationship about a circular form;

Fig. 5 is a plan view of a form having grooves conforming with the axial grooves in the turbine spindle;

30 Fig. 6 shows the blades assembled in their proper cooperative relationship with respect to the forms shown in Figs. 4 and 5, the forms being shown in section;

Fig. 7 is a vertical section through a portion of the turbine spindle and a hydraulic press for simultaneously inserting a circumferential row of blades in their respective spindle grooves;

Fig. 8 is a plan view of a form used for completing the insertion of the blades in the spindle grooves; and

Fig. 9 is a central vertical sectional view of the form shown in Fig. 8.

The turbine, reference being had to Fig. 1, comprises a spindle 1 having two circumferentially extending rows of blades 2 and 3, which rows are axially spaced apart to cooperatively receive therebetween a row of stationary blades 4 secured to the casing 6 in a conventional manner. The blades are prevented from moving in a lateral direction with respect to the circumferential blade rows by means of spacing blocks 7 and the conventional locking groove and ring arrangements 8. The casing 6 is provided with one or more groups of nozzle passages of which only one passage 9 is shown. The sealing means usually employed to prevent the escape of the driving fluid around the ends of the moving and stationary blades, which means are not essential for an understanding of the invention, have been omitted to simplify the disclosure. The blades 2 and 3 forming the circumferential blade rows

each have, as best shown in Figs. 2 and 3, a root portion 11, a body portion 12, a passage defining portion 13 presenting opposed concave convex passage defining surfaces 14 and 16, respectively, and an integral shroud portion 17. The concave surface 14 on one blade coacts with the convex surface 16 of the next adjacent blade to form therebetween a passage 18 for the driving fluid. The blades 2 define the passage 18 by having the coacting concave convex surfaces on adjacent blades disposed in partially nested relationship whereas the corresponding passage defining surfaces of the blades 3 are not disposed in partially nested relationship. Due to this difference in construction, the abutting side surfaces of the shrouds 17 and of the body portions 12 of the blades 3 are plane surfaces whereas the corresponding surfaces of the blades 2 are curved. The blade pitch is essentially the same in both of the circumferential blade rows and whether the coacting concave convex passage defining surfaces on adjacent blades are disposed in partially nested relationship is determined by the inlet and outlet angles of the blades and by the width of the fluid passage.

As shown in Fig. 3, the dividing line between adjacent blades as defined by the curved abutting side surfaces of the shrouds 17 and the body portions 12 of the blades 2 does not coincide with concave fluid driving surfaces 14. This arrangement provides a fluid confining passage which is sealed at the outer and inner boundaries defined by the coacting concave convex surfaces 14 and 16, respectively. The fluid pressure within the passage is greatest at the outer and inner boundaries and with this construction, it is not necessary to have the same high degree of fit between the abutting surfaces on adjacent blades in order to avoid excessive leakage as it is when the dividing line coincides with the concave driving surface 14. In addition, this arrangement makes it possible to better regulate conditions affecting centrifugal stability as the center of gravity and the line of action of the centrifugal force is thereby displaced in a direction such that the desired centrifugal moment may be obtained with a blade having less mass.

The spindle 1, reference being had to Figs. 1 through 3, has a circumferential groove 19 approximately equal in width to the distance the blade roots are spaced apart to form the axially spaced circumferential blade rows and a circumferential row of spaced axially extending blade retaining grooves 21 of greater depth than the circumferential groove 19. The axial grooves 21 extend laterally beyond the sides of the circumferential groove 19 distances approximately equal to the axial length of the root portions 11 of the blades 2 and 3. The walls of the axial grooves 21 and the corresponding side walls of the root portions 11 of the blades 2 and 3 and of the spacing block 7 are slotted as shown in Fig. 2 to provide mutually coacting retaining surfaces 22. The relative depth of the grooves 19 and 21 should be such that the portion of the walls of the grooves 21 which lie below the bottom surface of the groove 19 present retaining surfaces effective to secure the spacing block 7 against movement in a radial direction.

The best procedure to follow in order to obtain the previously described arrangement of grooves is to first cut the circumferential groove 19, the cross-sectional configuration of which is preferably rectangular and then to cut the axial retaining grooves 21. This procedure enables each

5 of the axial retaining grooves 21 to be made with a single broaching operation thereby materially reducing the time required and the machining costs. The concave convex passage defining surfaces 14 and 16 and the root portion 11 of each of the blades 2 and 3 are accurately machined and finished as is also the same one side surface of each blade as defined by the side surfaces of the body and shroud portions 12 and 17 respectively which are adapted to abut the body and shroud portions of the next adjacent blade. The opposite side of each blade is machined to the approximate dimension desired there being excess material left on this side which is removed when the blades are fitted.

Each blade after being machined as previously described is then fitted for insertion in its respective groove. Fitting is accomplished by inserting a blade about half-way in its respective groove, which blade and groove may be arbitrarily selected, in the first instance, and by inserting in the next adjacent groove with respect to the accurately machined side of the blade a measuring device which permits a measurement 20 of the distance between a surface of the measuring device and the accurately machined side of the blade. This measurement accurately determines the material to be machined from the unfinished side of the blade which is to be inserted 25 in the groove containing the measuring device. The blade and the groove in which the blade was partially inserted are marked for future identification and this blade and the measuring device are then removed. A blade is then selected for insertion in the groove from which the measuring device was removed and is marked for further machining as indicated by the measurement 30 previously taken. This blade and the measuring device are then inserted in the proper grooves, the measurement taken and identification markings made as previously described and this procedure is repeated until all of the blades have been measured and identified with respect to the 35 grooves in which the blades are to be inserted in their proper cooperative relationship. The unfinished sides of the blades are then machine finished as indicated by the measurements.

The blades for the first circumferential blade row in which the fluid passages 18 are defined by having the coacting concave convex surfaces on adjacent blades disposed in partially nested relationship as represented by the blades 2 in Fig. 3 must now be inserted in their respective grooves in pairs to determine whether further hand fitting is necessary. A pair of blades previously 40 fitted with respect to one another as above described are held together in proper cooperative relationship and an attempt is made to simultaneously insert the blades in their respective grooves. The proper grooves can be readily identified from the markings previously applied. If the blades cannot be simultaneously inserted, further hand fitting is done. When this first pair of blades has been properly fitted, assuming that 45 further hand fitting was found necessary, the blades are removed and the operation is repeated using pairs of blades consisting of one blade of the pair previously fitted and the next adjacent blade until all of the blades have been thus finally fitted. This method of fitting the blades need 50 not be used for the circumferential blade row formed with the blades 3 as these blades can be separately inserted and fitted in the usual manner.

55 After all of the blades 2 for the first circum-

ferential blade row have been finally fitted, the blades are placed in their proper order as determined by the identifying marks previously applied and arranged in their proper cooperative relationship about the form 24 as shown in Fig. 4. The diameter of the form 24 is equal to the diameter of the spindle 1 measured at the bottom of the axial grooves 21 and the blades may be arranged in their proper cooperative relationship with their roots contacting the form 24 as shown in Figs. 4 and 6 by moving the individual blades in a radial direction with respect to the form 24. Any suitable means such as the flexible band 26 may be placed about the blades as shown in Figs. 4 and 6 and tightened to hold the blades in position against the form 24. It should be understood that the arrangement of the blades about the form 24 as previously described is effected on a table or other suitable supporting surface 27 (Fig. 6). The form 24 has an annular, coaxially extending guide member 28 and the thickness of the form 24 is preferably considerably less than the axial length of the blade roots 11 as shown in Fig. 6.

The outer periphery of the annular form 29 shown in Fig. 5 has slotted blade retaining grooves 31 which are identical in cross-sectional configuration, arrangement and number to the axial grooves 21 in the spindle 1. The form 29 also has a plurality of circumferentially spaced threaded holes 32 located on a circle concentric with respect to the center of the form. The inside diameter of the form 29 is greater than the diameter of the spindle shaft as shown in Fig. 7 and substantially equal to the outside diameter of the annular guide member 28 on the form 24. The guide member 28 serves to center the form 29 with respect to the form 24 as shown in Fig. 6. After the blades have been arranged about the form 24 and secured thereto as described in the preceding paragraph, the form 29 is placed upon the form 24 to effect the relationship shown in Fig. 6 with that portion of the roots of the blade which extend above the form 24 disposed in the grooves 31 of the form 29. The roots of the blades fit the grooves 31 in the form 29 with sufficient snugness so that when the retaining band 26 is loosened, the form 29 and the blades 2 may be lifted bodily from the form 24. After removing the form 29 and the blades 2 from the form 24, the retaining band 26 may be again tightened if it is so desired.

The blades 2 which are to form the first circumferential blade row on the spindle 1 are now arranged and secured on the form 29 in their proper cooperative relationship with respect to one another and all that remains to be done is to so position the form 29 with respect to the spindle 1 that the roots of the blades are in axial alignment with the corresponding grooves 21 and to simultaneously insert the roots of the blades in their respective grooves. Apparatus suitable for simultaneously pressing the blades into their respective grooves is shown in Fig. 7 and comprises a hydraulic press 33 having a base 34, a cylinder 36 containing an actuating piston 37 and a guide portion 38, a press plate 39 formed integral with the guide portion 38, and a hollow cylindrical member 41 of welded construction which is removably secured to the press plate 39 by means of bolts 42. The end of the cylindrical member 41 opposite the end secured to the press plate 39 consists of an annular face plate 43 having an inside diameter greater than that of the spindle shaft and circumferentially

spaced bolt holes 44 equal in number and arranged for alignment with the threaded holes 32 in form 29. The side wall of the cylindrical member 41 is provided with openings 46 for inserting cap screws into the holes 44 in the face plate 43 which enables the form 29 to be rigidly secured to the annular face plate 43 of the cylindrical member 41 by means of cap screws 47 as shown in Fig. 7. Fluid for operating the press is admitted and drained from opposite sides of the piston 37 as desired by means of the pipes and ports 48 and 49, respectively.

The form 29 with blades 2 mounted thereon as previously described is attached to the face plate 43 by means of the cap screws 47. The spindle is supported in any suitable manner such as by means of a crane (not shown) and the spindle and press are brought into the cooperative relationship shown in Fig. 7 with the end 15 of the spindle shaft extending within the hollow cylindrical member 41 in coaxial alignment with the cylinder 36 of the press 33 so that the cylindrical member 41 may be reciprocated in coaxial alignment with respect to the spindle 1 and the axial grooves 21. The roots 11 of the blades 2 may then be readily brought into axial alignment with their respective grooves in the spindle 1 by rotating either the spindle 1 or the cylindrical member 41 with respect to the press face 20 plate 39. In the arrangement shown, the blade roots 11 and the grooves 21 are brought into proper alignment by slowly rotating the spindle 1, which is held against axial movement in a direction away from the press by a fixed means 30 35 51, in any desired manner. When the blade roots 11 and the grooves 21 are properly aligned, the press 33 is operated to move the form 29 towards the spindle 1 and the blades are simultaneously pressed into their respective grooves until the form 29 abuts the side of the spindle 1. The cap screws 47 which secure the form 29 to the face plate 43 are then removed and if the flexible retaining band 26 has not already been removed, it is removed at this time. The press 45 is then operated to move the face plate 43 away from the spindle 1 which leaves the form 29 suspended on the spindle 1 by means of the blades 2.

Figs. 8 and 9 show an annular form 52 which 50 is adapted to be secured to the face plate 43 in order to completely insert the blade roots 11 into the grooves 21. One side of this form is provided adjacent its outer periphery with a circular row of radially and normally extending projections 53. The projections 53 are equally spaced circumferentially of the form and are equal in number to the axial retaining grooves 21 in the spindle 1. The side surfaces of the projections 53 are preferably defined by radial planes and their 55 circumferential width is such that when the projections 53 are moved axially into the grooves 21, the plane side surfaces of the projections will cooperate with the walls of the grooves and prevent the projections from bending. The radial length of the projections 53 should approximately 60 equal the radial depth of the grooves 21, but in no event should the diameter of the circle defined by the inner ends of these projections be less than the diameter of the spindle 1 measured at the bottom of the grooves 21. The length of the projections in a direction normal to the said one side of the form 52 should be at least equal to the distance the blades have yet to be moved in order to completely insert the blade roots 11 65 into the grooves 21. Form 52 is provided with

threaded holes 54 arranged to align with the holes 44 in the face plate 43 and its inside diameter is greater than the diameter of the spindle shaft.

The form 52 is now secured to the face plate 43 in the same manner as was the form 28 and if the spindle 1 has not been rotated with respect to the press 33 since the form 28 was removed, the projections 53 will be in axial alignment with the blade roots 11 and the grooves 21. In any event, this alignment is established and the press operated to move the face plate 43 towards the spindle thereby engaging the projections 53 with the blade roots 11 and forcing the blades into their proper position within the grooves 21. The press is then operated to withdraw the face plate 43 from the vicinity of the spindle, the forms 28 and 52 are removed, and the locking arrangement 8 applied to secure the blades against lateral movement with respect to the circumferential blade row. If the blades 3 and the spacing blocks 7 were inserted before the blades 2 nothing further remains to be done, but it may be desirable to insert the spacing blocks 7 and the blades 3 after the blades 2 have been inserted. This may be done with the arrangement shown as the spacing blocks 7 and the blades 3 can be separately inserted at the opposite end of the grooves 21. Obviously, if the operating pressures, temperatures, etc. dictate the use of blades in the second circumferential blade row having coacting concave convex passage defining surfaces disposed in partially nested relationship, these blades would be simultaneously inserted in the manner described with respect to the blades 2. In this event, the blades forming the second circumferential blade row would be inserted first.

The use of a hydraulic press or any other suitable type of machine for forcing the blades into the grooves is not essential as the blades may be manually inserted by using the types of forms disclosed or any other suitable means on which the blades can be arranged in their proper cooperative relationship, retained in this position, and the roots simultaneously inserted in their respective grooves. In this connection, it should be obvious that the cross-sectional configuration of the blade roots and of the retaining grooves may be varied as desired. The invention is obviously applicable to all types of turbines in which one or more circumferential blade rows are formed by blades having coacting concave convex passage defining surfaces disposed in partially nested relationship and it should be understood that it is not desired to limit the invention to the particular features of construction herein shown and described, as various modifications within the scope of the claims may occur to persons skilled in the art.

It is claimed and desired to secure by Letters Patent:

1. The method of assembling turbine blades in a circumferential row of spaced axially extending side entry retaining grooves, the cross-sectional configuration of which conforms with that of the blade roots, with the opposed passage defining surfaces on adjacent blades disposed in nested or in partially nested relationship which comprises fitting the blades to obtain the necessary cooperative relationship between coacting surfaces on adjacent blades, placing the blades together in their proper cooperative relationship and securing the blades in this position, moving the blades thus secured together into a position such that the root portion of each blade is in substantial axial alignment with a groove in

the circumferential groove row, and simultaneously inserting the roots of the individual blades into the axial retaining grooves.

2. The method of assembling turbine blades in a circumferential row of spaced axially extending side entry retaining grooves, the cross-sectional configuration of which conforms with that of the blade roots, with the opposed passage defining surfaces on adjacent blades disposed in nested or in partially nested relationship which comprises successively inserting, fitting and removing pairs of blades consisting of one blade of the pair previously fitted and the next adjacent blade until all blades have been inserted and fitted with respect to adjacent blades to obtain the necessary cooperative relationship between coacting surfaces, placing the blades together in their proper cooperative relationship and securing the blades in this position, moving the blades thus secured together into a position such that the root portion of each blade is in substantial axial alignment with a groove in the circumferential groove row, and simultaneously inserting the roots of the individual blades into the axial retaining grooves.

3. The method of assembling turbine blades in a circumferential row of spaced axially extending side entry retaining grooves, the cross-sectional configuration of which conforms with that of the blade roots, with the opposed passage defining surfaces on adjacent blades disposed in nested or in partially nested relationship which comprises simultaneously inserting a pair of adjacent blades into adjacent grooves in the circumferential row, fitting the blades to obtain the necessary cooperative relationship between coacting surfaces and then removing the blades from the grooves, repeating this operation using pairs of blades consisting of one blade of the pair previously fitted and the next adjacent blade until all blades have been inserted in their respective grooves and fitted with respect to adjacent blades, placing the blades together in their proper cooperative relationship and securing the blades in this position, moving the blades thus secured together into a position such that the root portion of each blade is in substantial axial alignment with the corresponding groove in the circumferential groove row, and simultaneously inserting the roots of the individual blades into the corresponding axial retaining grooves.

4. A moving blade assembly for elastic fluid turbines comprising a spindle having a circumferential row of spaced axially extending and substantially straight side entry blade retaining grooves, a blade secured in each groove, said blades each including a convex and a concave fluid directing side surface, and said grooves and blades being so constructed and arranged that the convex side surface on each blade is disposed in partially nested passage defining relation with respect to the concave side surface on the next adjacent blade.

5. A moving blade assembly for elastic fluid turbines comprising a spindle having a circumferential row of spaced axially extending and substantially straight side entry blade retaining grooves each of which is of sufficient length to retain two blades in axially spaced relation such that the blades in the circumferential row of axially extending grooves coact and form axially spaced circumferential blade rows adapted to receive therebetween a circumferential row of stationary blades, two blades secured in each groove in axially spaced blade row forming relation,

said blades each including a convex and a concave fluid directing side surface, and said grooves and blades being so constructed and arranged that the convex side surface of each blade in one circumferential blade row is disposed in partially nested passage defining relation with respect to the concave side surface on the next adjacent blade in said one row.

6. A moving blade assembly for turbines in which circumferential blade rows are axially spaced to receive therebetween a circumferential row of stationary blades comprising a spindle having a circumferential groove approximately equal in width to the distance the blade roots are to be spaced apart to form the axially spaced blade rows, a circumferential row of spaced axially extending side entry retaining grooves each of which is of greater depth than said circumferential groove and extends laterally beyond the sides thereof thereby providing axially spaced blade root retaining portions, two blades in each axial groove having their root portions secured in said spaced blade root retaining portions and forming axially spaced circumferential blade rows, and means including a spacing block disposed in that portion of each axial groove which is below and merges with the bottom portion of said circumferential groove operable to prevent movement of the blades longitudinally of the axial retaining grooves.

7. A moving blade assembly providing axially spaced circumferential blade rows adapted to cooperatively receive therebetween a circumferential row of stationary blades comprising a spindle having a circumferential groove approximately equal in width to the axial distance the blade roots are to be spaced apart to form the axially spaced blade rows, a circumferential row of spaced axially extending side entry retaining grooves each of which is of greater depth than said circumferential groove and extends laterally beyond the sides thereof, a spacing block disposed in that portion of each axial groove which is below and merges with the bottom portion of the said circumferential groove, two blades secured in each axial groove with the adjacent ends of their root portions abutting opposite sides of said spacing block, and means operable to prevent movement of the blades longitudinally of the retaining grooves.

8. A turbine spindle having means for retaining blades in circumferential rows axially spaced apart to cooperatively receive therebetween a circumferential row of stationary blades comprising a circumferential groove approximately equal in width to the distance the blade roots are to be spaced apart to form the axially spaced circumferential blade rows, and a circumferential row of spaced axially extending side entry retaining grooves each of which is of greater depth than said circumferential groove and extends laterally beyond the sides thereof thereby providing axially spaced root retaining portions and an intermediate spacing block retaining portion.

9. A turbine spindle having means for retaining blades in circumferential rows axially spaced apart to cooperatively receive therebetween a circumferential row of stationary blades comprising a circumferential groove approximately equal in width to the distance the blade roots are to be spaced apart to form the axially spaced blade rows, and a circumferential row of spaced

axially extending side entry retaining grooves each of which is of greater depth than said circumferential groove and extends laterally beyond the sides thereof distances approximately equal to the axial length of the root portions of the blades adapted to be secured therein thereby providing axially spaced blade root retaining portions and an intermediate spacing block retaining portion.

10. A turbine spindle having means for retaining blades in circumferential rows axially spaced apart to cooperatively receive therebetween a circumferential row of stationary blades comprising a circumferential groove approximately equal in width to the distance the blade roots are to be spaced apart to form the axially spaced blade rows, and a circumferential row of spaced axial side entry retaining grooves each of which is of greater depth than said circumferential groove and extends laterally beyond the sides thereof distances approximately equal to the axial length of the root portions of the blades adapted to be secured therein, said axial grooves each having their side surfaces including the portions which are below and merge with the bottom of the circumferential groove slotted to provide retaining surfaces.

11. A turbine spindle having means for retaining blades with root portions presenting opposed multiple slotted retaining surfaces in circumferential rows axially spaced apart to cooperatively receive therebetween a circumferential row of stationary blades comprising a circumferential groove approximately equal in width to the distance the blade roots are to be spaced apart to form the axially spaced blade rows and of a depth less than that of the blade roots by at least the width of a retaining slot, and a circumferential row of spaced axially extending side entry retaining grooves each of which has a cross-sectional configuration conforming with that of the blade roots and each of which extends laterally beyond the sides of said circumferential groove distances approximately equal to the length of the root portions of the blades to be secured therein.

12. A turbine spindle having means for retaining blades with root portions presenting opposed multiple slotted retaining surfaces in circumferential rows axially spaced apart to cooperatively receive therebetween a circumferential row of stationary blades comprising a circumferential groove approximately equal in width to the distance the blade roots are to be spaced apart to form the axially spaced blade rows and of a depth less than that of the blade roots by at least the width of a retaining slot, and a circumferential row of spaced axially extending side entry retaining grooves each of which has a depth conforming with that of the blade roots and each of which extends laterally beyond the sides of said circumferential groove distances approximately equal to the axial length of the root portions of the blades to be secured therein, said axial grooves including the portion below the bottom of the circumferential groove having slotted retaining surfaces adapted to contact with the slotted retaining surfaces of the blade roots.

ROBERT C. ALLEN.
JAMES WILSON.
